UNITED STATES PATENT OFFICE.

DEWITT C. WEED AND FREDRIC ATKIN, OF VICKERY, OHIO, ASSIGNEES OF ONE-THIRD TO SAMUEL M. SMART, OF SAME PLACE.

CULTIVATOR-PLOW.

SPECIFICATION forming part of Letters Patent No. 606,609, dated June 28, 1898.

Application filed January 4, 1898. Serial No. 665,547. (No model.)

To all whom it may concern:

Be it known that we, DEWITT C. WEED and FREDRIC ATKIN, citizens of the United States, residing at Vickery, in the county of

5 Sandusky and State of Ohio, have invented certain new and useful Improvements in Cultivator-Plows; and we do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to improvements in plows, and more particularly to the class of plows known as "cultivators," and has for its object the production of a drag plow or cultivator wherein the shovels or cutter-shovels 20 are of peculiar shape and may be adjusted by raising or lowering to any height and in which the said cutter-shovels are set at such an angle to the moving direction of the plow or cultivator that the dirt will be properly furrowed and roots and other matter readily severed by the cutter-shovels as they pass through the ground.

25 The invention further consists in the novel arrangement and combination of the several 30 parts of the device hereinafter described, illustrated in the drawings, and more particularly pointed out in the claims hereunto appended.

In the drawings, Figure 1 is a perspective view of the device partly broken away to 35 show the arrangement of the shovels. Fig. 2 is a bottom plan view of the cultivator, showing the angle at which the said cutter-shovels are set; and Fig. 3 shows details of construction.

40 Similar letters indicate corresponding parts in all the figures.

Referring to the drawings by letter, V indicates a V-shaped frame having a brace or cross-piece A therein. This frame V has secured upon its upper side the handles a, which are joined by the rung a' and braced at the rear of said frame by the supports a². In the front end of said frame B is a gage-wheel B, adjustably secured therein by screw-

threads or otherwise, so that it can be raised 50 or lowered vertically at will.

C is a hook secured to the front end of said frame V, to which the moving power is attached.

D is a metallic post having on the lower end 55 thereof, integral therewith, and set at about right angles thereto a cutter-shovel D'. The cutter-shovel D' has a flaring shape, as shown, and has its forward edge sharpened to cut roots and other things with which it comes 60 into contact. D² is a bracket secured to the piece A in the frame V and is provided with an offset therein for receiving and holding the said post D securely and firmly in the said frame.

d is a brace-rod secured at one end to the front of the frame V and at the other upon the post D at a point d', and serves the purpose of holding the said post rigid when the cultivator is in use. The front of the post D, 70 between the point d' and the cutter-shovel D', is sharpened to form a cutter D², as shown.

E E are cutter-shovels secured to the rear part of the frame V, on the sides thereof, as shown, and are braced thereto by brace-rods 75 E' E'. These cutter-shovels E E are of peculiar shape and are formed by taking a piece of iron or steel and bending it to the shape shown in the drawings, the portion e thereof being the vertical or supporting portion and 80 the part e' the cutter-shovel. This portion e' is set at about right angles to the upright portion and thrown slightly back and the front edge thereof sharpened to form a cutter. The part e is provided with a number of openings 85 c c c for the purpose of permitting a vertical adjustment of the said shovels and also to afford a means whereby they may be braced against displacement when the device is in use.

The upright portions E have the front 90 edge thereof, between the openings c c c and the portion e', sharpened. When these shovels are secured to the frame, they will set at an angle of forty-five degrees, more or less, to the direction of the plow.

95 By the use of this cultivator the ground may be loosened up, and by reason of the angle at which the said cutter-shovels are set the

roots, &c., will be readily severed instead of dragged along, as is the case where these cutter-shovels are at right angles to the direction of the plow. By this construction the plow 5 is not only easier to run, but performs its work to much better advantage. It is apparent from the construction of this device that it may be used to great advantage as a sod-cutter, as the cutters may be set so as to cut 10 the sod any thickness desired and of proper width.

Having thus described our invention, we claim—

1. In a cultivator of the character described 15 the combination of the V-shaped frame provided with suitable handles, with a cutter-post secured to the middle of said frame and having on its lower end at right angles thereto a cutter-shovel, and on the rear of said 20 frame the cutter-shovels E, E, having the cut-

ter portions thereof at right angles and set at an angle to the direction of movement of the plow, as set forth.

2. In a cultivator of the character described 25 a cutter-shovel located near the front of said plow and having a flaring cutting edge, and cutter-shovels, substantially as described, located near the rear of said plow-frame and having their cutting-shovels set backward at an angle to the direction of movement of the 30 plow, substantially as and for the purpose set forth.

In testimony whereof we affix our signatures in presence of two witnesses.

DEWITT C. WEED.
FREDRIC X ATKIN.
